US0D1094900S

(12) **United States Design Patent** (10) Patent No.: **US D1,094,900 S**
(45) Date of Patent: ** Sep. 23, 2025

(54) **RESPIRATORY PROTECTION HOOD**

(71) Applicant: **L'Air Liquide, société anonyme pour l'Étude et l'Exploitation des procédés Georges Claude**, Paris (FR)

(72) Inventors: **Rachid Makhloche**, Paris (FR); **Arnaud Barrère**, Gennevilliers (FR); **Jérémie Galland**, Paris (FR)

(73) Assignee: **L'AIR LIQUIDE, SOCIETE ANONYME POUR L'ETUDE ET L'EXPLOITATION DES PROCEDES GEORGES CLAUDE**, Paris (FR)

(**) Term: **15 Years**

(21) Appl. No.: **35/520,365**

(22) Filed: **Nov. 30, 2023**

(80) **Hague Agreement Data**

Int. Filing Date: **Nov. 30, 2023**

Int. Reg. No.: **DM/235682**

Int. Reg. Date: **Nov. 30, 2023**

Int. Reg. Pub. Date: **Mar. 22, 2024**

(30) **Foreign Application Priority Data**

Jun. 2, 2023 (EM) 015023593-0001

Jun. 2, 2023 (EM) 015023593-0003

(57) **CLAIM**

The ornamental design for a respiratory protection hood as shown and described.

DESCRIPTION

2. Respiratory protection hood

2.1: Front

2.2: Left

2.3: Back

2.4: Right

2.5: Top

2.6: Bottom

2.7: Perspective

1 Claim, 7 Drawing Sheets
